CLAIM

The ornamental design for a suction brush, as shown and described.

DESCRIPTION

FIG. 1 is a side perspective view of a suction brush, showing my new design;

FIG. 2 is a perspective view taken from the opposite side thereof;

FIG. 3 is a front elevational view thereof;

FIG. 4 is a bottom view thereof;

FIG. 5 is a top view thereof.

The conventional electrical cord has been shown fragmentarily in all views for ease of illustration.
